UNITED STATES PATENT OFFICE

2,318,830

HONING MACHINE

George Crompton, Jr., Worcester, Mass., assignor
to Norton Company, Worcester, Mass., a corporation of Massachusetts

Application July 19, 1938, Serial No. 219,988

10 Claims. (Cl. 51—34)

The invention relates to honing machines. One object of the invention is to provide an automatic honing machine. Another object of the invention is to achieve uniformity in the finishing of cylinder bores of automobile cylinder blocks. Another object of the invention is to eliminate classification of the automobile cylinders as A, B, C, D, E, etc., which classification is now resorted to on account of failure of present production methods to bring cylinder bores to uniform size. Another object of the invention is to provide a honing machine which shall remove a substantial amount of stock from the cylinder bore. Another object of the invention is to provide an automatic control for a machine tool of the type indicated which may be incorporated in various types and sizes of machine hones. Another object of the invention is to provide a honing tool with a simple electrically actuated control for expansion and contraction. Another object of the invention is to provide honing tools and controls therefor which may be applied to existing machine tool hones to make them automatic or semi-automatic in operation.

Another object of the invention is to provide a honing tool which may be readily used in honing machines now existing and the expansion and contraction of which can be readily controlled at a distance while the machine is in operation. Another object of the invention is to provide a compact honing tool with electric actuation for expansion and contraction in the tool itself. Another object of the invention is to provide a honing tool which can be contracted by directing electric current to it in one direction and which can be expanded by directing electric current to it in the opposite direction. Another object of the invention is to provide an automatic gauging instrumentality measuring the bore of a work piece which is being honed. Another object of the invention is to provide gauging apparatus for several bores of a work piece being simultaneously honed by a multi-spindle honing machine so organized that only when all the gauges enter the bore will the honing tools be withdrawn from the work piece. Other objects will be in part obvious or in part pointed out hereinafter.

The invention accordingly consists in the features of construction, combinations of elements, and arrangements of parts, all as will be illustratively described herein, and the scope of the application of which will be indicated by the following claims.

In the accompanying drawings showing two of

many possible embodiments of the mechanical features of this invention,

Figure 1 is a front elevation of a honing machine constructed in accordance with my invention;

Figure 2 is a side elevation of the upper part of the honing machine, partly in vertical section, showing the driving mechanism for the spindles;

Figure 3 is a view, partly in plan and partly in section, of the machine, further illustrating the spindle driving mechanism, the section being taken along the line 3—3 of Figure 2;

Figure 4 is a fragmentary sectional view taken along the line 4—4 of Figure 2;

Figure 5 is a fragmentary side elevation, on an enlarged scale, looking at the left-hand side of the machine behind the pump, illustrating certain of the controlling devices for the hydraulic reciprocating head actuating means;

Figure 6 is an enlarged vertical axial sectional view taken on the line 6—6 of Figure 1, showing the honing tool, the work piece and the gauge mechanism;

Figure 7 is a horizontal sectional view taken on the line 7—7 of Figure 6, showing the switches;

Figure 8 is an enlarged view, partly in side elevation and partly in vertical section, illustrating the control for stopping the head in its upper position;

Figure 9 is an enlarged fragmentary axial sectional view through a pair of collector rings and insulator therefor mounted on the several spindles of the honing tools to lead electric current to the tools;

Figure 10 is a radial sectional view showing the motor in a honing tool, the section being taken on the line 10—10 of Figure 6;

Figure 11 is a wiring diagram;

Figure 12 is a vertical axial sectional view of the driving portion of a honing tool according to another embodiment of the invention.

The invention is illustrated applied to a honing machine of the general type disclosed in United States Letters Patent No. 1,783,019 of Albert M. Johnson. The invention so far as it resides in the honing tool itself is shown embodied in a honing tool of the general type illustrated by United States Letters Patent No. 1,912,025 to Frederick G. Wacker and Herman W. Zimmerman. I shall hereinafter refer to these patents respectively as the Johnson patent and the Wacker patent.

As in the case of the Johnson patent, and referring now to Figure 1, the machine comprises a base 1 upon which is fixed an upright column 2 frontwardly provided with a pair of vertical slide-

ways 3. A work supporting table 4 having slidably adjustable guiding supports on the ways 3 is further supported from the base 1 by means of adjustable elevating screw standards 5. A piece of work is shown supported on the table comprising in the present instance a four cylinder internal combustion motor block 6 suitably clamped upon an adapter block 7 which rests upon the table 4.

Referring to Figures 1 and 2, mounted upon the upper end of the column 2 is a main housing 8 having a pair of upright auxiliary housings 9 and 10 extending frontwardly therefrom in spaced relation, the lower ends of which are positioned above the work supported on the table 4. The auxiliary housings 9 and 10 each support a vertically positioned spindle driving shaft 11. The spindle shafts and their associated parts being similarly constructed will be described as to one only and similar reference numerals applied to both. The shaft 11 is preferably provided with a thrust collar 12 which engages an antifriction bearing 13 secured to the upper end of a guide sleeve 14. The sleeve 14 extends through the lower end of the auxiliary housing 9 and is provided with spaced bearings 15 and 16 therein.

Referring to the upper part of Figure 2, the upper end of the spindle driving shaft 11 is splined and extends through the upper wall of the auxiliary housing 9. Within the housing 9 and in longitudinally slidable relation to the splined portion of the shaft 11 there is mounted on the shaft a sleeve 17 which is keyed to the shaft. The sleeve 17 is supported in ball bearings 18 and 19 which are supported in a portion of the housing 9, as clearly shown in Figure 2.

Secured to the upper end of the sleeve 17 and located in the auxiliary housing 9 is a spur gear 20 which meshes with a spur gear 21 mounted on a stub shaft 22 which is journalled in ball bearings 23 and 24 mounted in a bearing hub 25 that is integrally connected to the auxiliary housing 9. Fastened to the lower end of the stub shaft 22 is a bevel gear 26. Comparing now Figures 2 and 3, and remembering that there are two bevel gears 26, they mesh with bevel gears 27 fastened to a cross shaft 28 in the housing 8. As indicated in Figures 2 and 3, fastened to one end of the cross shaft 28 is a gear 32 which meshes with a gear 33 fastened to a shaft 34 which is journalled in the housing 8. The gear 33 is driven by a pinion gear 36 which is secured to a shaft 37 which can be clutched to an armature shaft 38 of a motor 39 which is mounted on a suitable bracket 40 supported upon the wall of the housing 8. The clutch to couple the shaft 37 to the shaft 38 is generally indicated by the numeral 41 and is described more in detail in the Johnson patent. The mechanism may include a brake 42 the details of which will not herein be described as reference may be had to the Johnson patent; suffice it to say that a crank 48 controls both the brake and the clutch and when the crank is in its extreme right-hand position (Figure 3) or moved in the clockwise direction in plan view, the clutch 41 is engaged and the brake 42 is released, while movement to the left or in a counterclockwise direction releases the clutch and applies the brake. By means of the foregoing mechanism, the motor 39 drives both spindle shafts 11, and the clutch and brake means described in the Johnson patent are provided to stop and start the shafts 11. Also it will be noted these shafts 11 may move up and down without in any way interfering with the rota-

tive driving mechanism on account of the provision of the splined connection between shafts 11 and sleeves 17.

Referring now to Figures 1 and 2, positioned below the lower ends of the auxiliary housings 9 and 10 and fastened to the sleeves 14 is a reciprocating head 63. Referring now to Figure 4, the head 63 is hollow and the sleeves 14 which constitute reciprocating guideways are secured to the upper wall of the head 63, each of the sleeves having an annular flange 64 positioned in annular pockets provided in the upper wall of the head and secured thereto as by bolts. The spindle driving shafts 11 extend into the ends of the head 63, being supported at their lower ends in ball bearings 65 secured in the lower ends of the sleeves 14.

Still referring to Figure 4, fastened to the lower ends of the driving shafts 11 are driving gears 66. These gears 66 mesh with gears 67 fastened to short shafts 68 journalled in the head 63. Each shaft 68 has likewise fastened to it a gear 69 which meshes with gears 70 and 71 respectively secured to spindle supporting socket members 72, 73, the latter being carried in spaced ball bearings 74 mounted in bearing bosses 75 formed in the lower wall of the head 63. Thus each shaft 11 drives a pair of spindle supporting socket members 72, 73 which are journalled in the head 63 and the sockets 72 and 73 are rotated in the same angular direction and at the same velocity, the gears 70 and 71 not meshing with each other but both meshing with the driving pinion 69 which is shown in dotted lines in Figure 4. As shown in Figure 1, there are four socket members 72, 73 and they are located in pairs, each of sockets 72 being located the same distance from adjacent socket 73, although the space between sockets 72 is not the same as the space between sockets 72 and 73. The spacing shown, however, is the same as that of the cylinder bores in the typical automobile cylinder block 6, and by providing different heads 63, any other spacing may be provided for. Furthermore, the machine tool may be widened by adding additional auxiliary housings like the housings 9 and 10 and repeating the mechanism therein contained to drive any number of spindle sockets 72, 73 desired, thus if desired providing a machine of this type for the honing of six cylinder blocks and eight straight-in-line cylinder blocks.

Reciprocating movement of the head 63 is accomplished by means of an hydraulically actuated piston, not shown, located in a cylinder 77 which, as shown in Figure 1, is fastened to the housing 8 and located between the auxiliary housings 9 and 10. As shown in Figure 1, a piston rod 78 extends from the lower end of the cylinder 77 and is attached to the head 63. This piston rod 78 may extend upwardly beyond the cylinder 77 to cause the same pressure to be exerted to move the head 63 up and down. As more fully described in the Johnson patent, a balancing cylinder 79 may be provided to compensate for the weight of the head 63 and all associated parts which move vertically.

The cylinder 77 is supported on the housing 8 by brackets 80 and 81 which are braced by means of tension rods 82 and 83. The upper and lower ends of the cylinder 77 are provided with ports 84 and 85 opening through the brackets 80 and 81 into communication with the interior of the cylinder. Referring now to Figure 5, there is provided a four-way controlling or reversing valve 86 having ports connected to pipes

87 and 88 which are connected to the ports 84 and 85. Pipe connections 89 and 90 to the valve 86 are respectively connected with the pressure side and the suction side (or the sump) of an oil pump indicated in Figure 3 by the numeral 91. The operative parts of this pump may be driven by a pinion gear 92 mounted on the shaft 37 engaging a gear 92a mounted on the pump shaft.

Referring again to Figure 5, the control valve 86 operates to direct pressure fluid alternately into the pipes 87 and 88 to send pressure fluid to the opposite ends of the cylinder 77 to reciprocate the head 63. At any given time one of pipes 87 and 88 contains fluid under pressure while the other one is the return pipe for the return of the fluid from the no pressure end of the cylinder. The valve 86 contains a piston, not shown, the position of which is determined by pilot valve 93 having pipe connections 94 and 95 with opposite ends of the four-way controlling and reversing valve 86. The pilot valve 93 likewise has pressure and exhaust pipe connections 96 and 97 with the pump 91. The pilot valve 93 includes a longitudinally moving piston controlling the ports through the pipe connections with the ends of the reversing valve 86, and this piston is controlled by a piston rod 98. I do not herein illustrate or describe the details of the pistons and ports in valves 86 and 93, the same having not been described in the Johnson patent either, since pilot and reversing valve constructions are now well known to those skilled in this art and any suitable pilot and reversing valves may be utilized, and so far as many features of my invention are concerned any other type of actuating, controlling and reversing mechanism might be substituted for that herein described, for example a mechanically operated and controlled mechanism, of which there are many types.

Resuming the description of this particular controlling and reversing mechanism, and referring again to Figure 5, the piston rod 98 carries a spring stop device comprising a rod 99 pivotally mounted at one end in a block 100 secured to the piston rod. The rod 99 has fastened thereto in spaced relation a pair of blocks 101 and 102 which have spring receiving recesses facing each other and holding springs 104 and 105. Between the blocks 101 and 102 is a block 103 which is engaged by the springs 104 and 105, thus offering resilient resistance to the movement of the block 103 along the rod 99. The block 103 is pivotally secured to a reversing lever 106 which is pivotally mounted on a stud 107 projecting from a bracket 108 secured to the side wall of the housing 10. The lever 106 extends to the other side of the stud 107 and terminates in a reversing lug 109 protruding from a counterweighted portion 109a of the lever 106. The pilot valve controlling mechanism is constructed to permit the movement of the pilot valve with a slight overrun in the valve operating lever 106 against spring tension, to assure the complete movement of the valve and protect it against possible damage by jamming. In some respects the pilot valve is a substitute for the load and firing mechanism, arrow point and cam device, or the snap-over detent, well known in machine tools for controlling a mechanical reversing mechanism and also used to some extent to control a main valve. Any one of such devices may be utilized to achieve a reversal of the rectilinear travel of the tools as distinguished from a mere stopping thereof.

The machine so far described is the machine of the Johnson patent and except in combination with the other features hereinafter explained, is not my invention. In fact, any other suitable honing machine tool may be substituted for the machine of the Johnson patent although my invention readily lends itself to incorporation in this machine. Although in the description which is to follow, some parts may be identified as parts of the Johnson patented machine, the operation and control as well as the several features of the machine are part of my invention, as will hereinafter appear.

Referring now to Figures 1 and 5, I provide a reciprocating control rod 110 which at the upper end passes through and is guided by a bracket 111 extending from the upper gear casing portion of the auxiliary housing 10. Adjustably fastened to this rod 110 are striking dogs 112 and 113, the striking portions of which are disks and arranged in the path of the reversing lug 109. Also adjustably mounted on the rod 110 and intermediate the dogs 112 and 113 is a shaped dog 114. This dog 114 when in the position shown in Figure 5, moves in the path of the lug 109 and will strike the lug 109 to reverse the head 63. However, when the rod 110 is given a slight turn either manually or by an automatic mechanism herein-after described, the striking portion of the dog 114 is moved out of the path of the lug 109. Referring now to Figure 8, there is provided a hand lever 116 fastened to the lower end of the rod 110 by means of which the rod 110 may be manually turned to swing the striking portion of the dog 114 out of the path of the lug 109. Referring now to Figures 1 and 8, fastened to the rod 110 are thrust collars 117 which secure it so far as vertical movement is concerned to a bracket 118 which is fastened to the side of the head 63. Thus it is 20 that the rod 110 moves upwardly and downwardly with the head 63. I provide a stop arm 119 fastened to and extending downwardly from the bracket 118 and extending into the path of movement of the hand lever 116 to prevent movement to the left (Figure 1) of the hand lever 116 beyond the position shown in Figure 1. In the position of 25 Figure 1, the operating portion of the intermediate dog 114 is in the path of the lug 109.

The reciprocating movement of the head 63 is 30 further controlled by a stop valve 122 (Figures 1 and 3) interposed in the main pressure line from the pressure pump 91 which normally allows oil to be directed under pressure to the four-way valve 86 but which may be moved to by-pass the oil back to the suction side of the pump. When 35 the valve 122 is so moved, the head 63 will come to a stop. This stop valve 122 is operated by an arm 123 connected to the valve stem 124 of the valve member of the stop valve 122. The arm 123 is mounted on a sleeve 125 which is journaled on a rod 126 extending between and journaled in brackets 127 and 128, the former fastened to the column 2 and the latter fastened to an upper part of the housing 8, as shown in Figure 1. Fastened to the inside rod 126 is an arm 130 which, as shown in Figure 3, is connected by a link 131 with the arm 48. Thus rotation of the rod 126 controls the brake and clutch mechanism. The sleeve 125 extends downwardly as far as and 40 is secured to the hub 132 of an operating lever 133 while the rod 126 extends below the hub 132 and is fastened to the hub 135 of an operating lever 136. By a latch mechanism fully described in the Johnson patent, the operating lever 133 45 may be connected to actuate the lever 136 or it

may be disconnected therefrom for independent control of the sleeve 125 and thereby the stop valve 122. Usually the two levers 133 and 136 are connected together and operate as a unit and thereby the controls more fully described herein-after serve automatically to stop the movement of the head and also to stop the rotation of the spindle sockets 72 and 73, thereby stopping the honing tools from rotating.

Referring now to Figures 1, 3 and 11, I provide an automatic control for the reciprocating movement to cause the honing tools hereinafter described to be raised out of the work piece by upward movement of the head 63 when all of the bores of the work piece have been honed to the desired diameter. On the top of the gear casing of the auxiliary housing 10 I fasten a solenoid 140 which has a core 141 connected by a link 142 with a lever 143 keyed to the rod 110. The rod 110 is splined at the top portion thereof to permit it to move through the lever 143 and the bracket 111 provides a bottom and top thrust bearing for the lever 143, the bracket 111 being forked shaped, as shown in Figure 1. The other end of the lever 143 is connected by means of a spring 146 to a spring anchor 147 secured to the gear casing of the auxiliary housing 10. The spring endeavors at all times to turn the rod 110 in a counterclockwise direction in plan view. Such action would remove the dog 114 from the path of the lug 109. During normal operation of the machine, however, the solenoid 140 overcomes the force of the spring 146 and holds the rod 110 to maintain the dog 114 in the path of the lug 109. Further movement beyond this point is prevented by the arm 119 which engages the operating handle 116. But whenever the solenoid 140 is deenergized the spring acts, swinging the arm 116 away from the stop 119 and swinging the dog 114 out of the path of the lug 109. It is a feature of my invention that the failure of the electric circuits for any reason thus causes the head 63 to rise and removes the honing tools from the cylinder bores, thus preventing any damage.

The dog 112 operates on the lug 109 as a reversing dog to reverse the direction of travel of the head 63. The dog 114 likewise operates on the lug 109 to reverse the direction of travel but as explained it can be moved out of the path of the lug 109. The dog 113 will also reverse the travel of the head 63, but I desire to stop the head 63 in its withdrawn position at the finish of a honing operation and, therefore, I provide an additional mechanism automatically to operate the stop valve 122 just before the dog 113 would engage the lug 109. Thereafter when the machine is started up again, the dog 113 first shifts the lug to reverse the reciprocating mechanism. That is to say, the head 63 may first rise by a slight distance, for example a fraction of an inch, before it descends to commence a honing operation.

Referring now to Figures 1, 3 and 8, I provide an arm 150 having a hub 151 fastened to the sleeve 125. The outer end of the arm 150 has a bore 152 receiving a spring 153 bearing against a movable pin 154 in the bore 152. There is a slot 155 in the top of the arm 150 through which projects an operating rod 156 secured to the pin 154. The operating rod 156 is provided with a knob 157 for convenient operation.

The bracket 118 has an inclined cam surface 160 which is in position to engage the pin 154 and when it does so, it will swing the arm 150 to the left, Figure 1, operating the valve 122 and 75

stopping the head 63 by by-passing pressure fluid. Figure 1 shows the cam surface 160 engaging the pin 154 and the head 63 is about to stop, the arm 150 having been moved partially but not through the entire distance. This action preferably takes place in advance of the dog 113 striking the lug 109 so that the head is brought to a stop without quite reversing the pilot valve 93 and thereby the reverse valve 86. This pre-caution eliminates the possibility of the head being reversed and travelling downward to cause the hones to reenter the finished work piece. When the operator is ready to hone a new work piece, however, he may push the knob 157 rearwardly which will place the pin 154 behind the bracket 118, allowing the lever 133 to be moved to reestablish the fluid pressure connections which will cause the head 63 to descend after a slight rise to cause the reversing action by pushing the lug 109 past the center point.

Referring now to Figure 2, the hones are a unit and are designated generally by the reference character 170. That is to say, the honing tools are completely removable from the machine 25 and are self-contained tools. Each hone 170 has a spindle 171 having a tapered end portion fitting in a socket 72 or 73. The spindles or shanks 171 are connected to lower spindles 172 (made of brass) by means of flexible couplings 173 the construction of which may be as described in the Johnson patent, or universal joints 30 may be substituted if desired. The provision of either one allows the honing tool to adjust itself in the bore of the cylinder block work piece, 35 for it must be understood that previous machining operations on an automobile cylinder block do not bring the axes of the several bores in the same plane or located exactly a given distance apart within the matter of a thousandth 40 of an inch or fractions thereof which are significant dimensions in a finishing operation of the nature performed by a machine of the invention.

Referring now to Figure 6, I have therein illustrated a honing tool which so far as the lower part thereof is concerned may be and preferably is constructed substantially in accordance with the Wacker patent aforesaid. The power or electric motor control hereinafter described, 45 however, is my own invention. I do not deem it necessary to describe the honing tool in detail (apart from the new features) since reference may readily be had to the Wacker patent and, furthermore, many and various types of honing tool instrumentalities may be substituted so far as my invention is concerned. Briefly, and referring to Figure 6, the Wacker patented hone includes an upper plate 175 which, however, I have somewhat enlarged, and a lower plate 176 which according to my invention has additional features hereinafter described, which plates 175 and 176 are connected by tie bars 177 as described in the Wacker patent. This forms a cage construction, guiding carriers 180 upon which are detachably mounted honing sticks 181. There may be any number of carriers 180 and honing sticks 181, for example four, as shown in the Wacker patent. Each carrier 180 has inclined surfaces 182 which are engaged by cones 183 mounted on a screw shaft 184 which extends through the upper plate 175 and is journaled in the lower plate 176. I adopt an inclination between the cam surfaces 182 and the cones 183 which represents a much smaller angle than is shown in the Wacker patent for reasons which

will presently appear. Garter springs 185 engage portions of the carriers and removably hold the structure in assembled relation. By rotating the screw shaft 184, the carriers 180 will be expanded or contracted depending upon the direction of rotation. Thereby the honing sticks 181 may be pressed against the bore of work piece 6 or withdrawn therefrom. The honing sticks 181 may be of any suitable type, for example bonded abrasive consisting of any of the usual abrasives, such as silicon carbide or alumina in its various forms, also diamonds, and the bond may be of any desired type, for example vitrified ceramic bond, resinoid bond including natural and synthetic resins, also rubber. While vitrified ceramic bonded abrasive sticks are usually preferred, I find special advantages in using a metal bond, for example that described in patent to Van der Pyl No. 2,072,051. The reason is that the machine of the present invention is adapted to remove a great deal more metal than has usually been removed in a honing operation and consequently a honing stick which will withstand severe usage is preferred.

My invention includes an electric motor contained between the spindle 172 and the lower part of the honing tool which has just been described. This motor is automatically controlled by a gauge mechanism to be described so that it gradually expands the honing tool until such time as the gauge indicates the bore is honed to the desired diameter, whereupon the current is reversed and the honing tool collapses. Referring now to Figure 6, the screw shaft 184 is formed with an enlarged portion 190 leaving a shoulder to make a thrust bearing resting upon the plate 175. Above the enlarged portion 190 is a reduced screw threaded portion 191. An internally threaded hub 192 of an armature having four arms 193 is mounted upon the threaded portion 191. Interposed between the hub 192 and the enlarged portion 190 is a commutator insulating disk 195 formed of any good insulator, such as hard rubber or molded resinoid. Suitably molded into or fastened to the commutator insulating portion 195 are four commutator sectors 196 made of copper or brass or other suitable metal. These sectors 196 are engaged by brushes 197, there being a pair of such brushes. The brushes 197 project from thimble-like brush holders 198 in which are springs 199 urging the brushes 197 into engagement with the sectors 196.

Figure 10 shows the armature consisting of the hub 192 and arms 193, which arms are wound with insulated wire, the ends of the wires being connected to each other and to the several commutator sectors 196 in a manner well understood in the electrical arts, this being a direct current motor.

The brush holders 198 extend through a cylindrical metal casing 200 which is integral with the lower spindle 172. The brush holders 198 may be surrounded by suitable insulating material in the form of sleeves 201, and thereby insulated from the casing 200. Binding post terminals having nuts 202 thereon have insulated wires 203 connected thereto to lead current to the motor. The field of the electric motor comprises a pair of permanent magnets 205 which are in the form of semi-cylindrical annuli the outer peripheries of which are screw threaded and which screw into internal threads in the casing 200. As indicated in Figure 10, the north poles are together and so also are the south poles, which forces the magnetic field across the arma-

ture. I prefer magnets 205 made by pressing together powdered electrolytic iron and other metals to make a good magnet structure, with subsequent heat treatment, because in this manner a permanent magnet having many times the strength of magnets previously known can be obtained. Finely divided electrolytic iron with the proper proportion of additional metal powders to make a good magnet steel is placed in a half annular mold and pressed with a strong pressure, thereafter heat treated and magnetized. The screw threads may be cut before the heat treating and magnetizing since the metal is soft at that time and this will not interfere with the magnetic qualities.

The foregoing motor drive for the cones 183 of the honing tool is characterized by extreme compactness and also reversibility merely by reversing the current in the armature since the field is constant. Referring now to Figures 2, 6 and 9, the wires 203 are led around the coupling 173 and may be held from flying out by taping them to the spindles 171 and 172. They connect to binding posts 210, 211 molded in a rubber or resinoid insulating disk 212 having metallic collector rings 213, 214, also molded therein. The binding post 210 may be an integral part of the collector ring 214 and the binding post 211 may be an integral part of the collector ring 213, as shown in Figure 9. Referring now to Figures 1, 2 and 9, brushes 215 and 216 respectively engage the rings 213 and 214. As shown in Figure 2, the brushes 215 and 216 are fastened to insulators 217 which are fastened to the head 63. An electric cable 220 has eight insulated wires therein which are severally connected to the brushes 215 and 216, the cable 220 being supported from any convenient stationary part of the machine and being also attached to the movable head 63 and extending in a loop between these points, as shown in Figure 1. Thereby electric current is introduced into the traversing and rotating honing tools 170 from a stationary source.

Referring now to Figure 6, I provide a gauge plug 225 for each cylinder bore to be honed. The table 4 and the adapter 1 have oversized openings 226 to receive the gauge plugs 225, yet allowing slight adjustment of the plugs 225 to compensate for irregularities in boring of the cylinder block 6. Each gauge plug 225 is in the form of a hollow piston and has a screw threaded stud 227 centrally located therein, projecting downwardly attaching the gauge plug to a coupling 228 which may be the same as the coupling 173 and which type of coupling is fully described and illustrated in Figure 14 of the Johnson patent. The coupling 228 is connected at its lower end to a rod 229 passing through a bearing boss 230 in the table 4. Switches controlling the operation of the machine are located in a long rectangular opening 231 in the table 4 and extend to the bottom thereof. Around the boss 230 and extending between the bottom of the bore 226 in the table 4 and the coupling 228 is a spring 232 which at all times urges the gauge 225 upwardly, trying to force it to enter the cylinder bore with which it is associated. I provide any suitable means for introducing kerosene into the bores to be honed, such as a nozzle 235 connected to piping 236 which connects to a pump, not shown. Kerosene is discharged from the cylinder bore and passes around the plug 225 when it is depressed, through the oversized bores 226, and thence through a passage 237 in the upper part

of the table 4 into a collecting tray 238 formed in the table 4.

At every downward stroke of the several honing tools, bunter projections 243 on the bottoms of the plates 176 engage gauges 225 and force them downwardly, permitting the honing tools to descend to the proper depth to assure even honing of the work piece. At all times prior to the entry of a particular gauge 225 into a particular bore, one pair of switches controlled by said gauge are maintained closed and another pair of switches controlled by said gauge are maintained open. When, however, a gauge enters a particular bore, thus signifying the honing of that bore to a given required size, the switches which were maintained closed are opened and the switches which were opened are closed. One pair of switches cause an energization of the motor in the honing tool which they control in a direction to expand the sticks 181 while the other pair of switches cause reverse action of the motor to contract the hone.

Referring now to Figures 6, 7 and 11, on the bottom of each rod 229 is an H shaped switch controller 245. Referring to Figures 6 and 7, the left-hand side piece 246 of the H member 245 has bosses 247 at its ends receiving headed studs 248 around which are springs 249. The heads of studs 248 engage switch arms 250 and 251, which arms 250 and 251 normally engage contacts 252 and 253.

On the other side of the H member 245 is a side piece 254 which has bosses 255 at the opposite ends thereof receiving headed studs 256 on which are coil springs 257. The heads of studs 256 are in position to engage switch arms 258 and 259 which when the rod 229 moves upwardly engage contacts 260 and 261. Switch arms 250 are journaled in insulating bosses 262 and 263 and springs 264 and 265 try to open the switches. The switch arms 258 and 259 are journaled in insulating bosses 266 and 267 and gravity may be relied upon to hold them open when not closed by the studs 256.

Referring now to Figure 11, I provide a source of direct current energy represented by the positive power line 270 and the negative power line 271. I provide a manually controlled switch 272 to connect the power lines 270 and 271 to main circuit power lines 275 and 280. Thus, assuming the switch 272 is closed, the power line 280 is positive and the power line 275 is negative.

Line 280 is connected by conductors 281 to the several terminals 252 and also to the switch arms 258. Negative line 275 is connected by conductors 282 to the terminals 261. Negative line 275 is connected by a conductor 283 to a rheostat 284 which is connected by line 285 to the solenoid 140. The other terminal of solenoid 140 is connected by a line 286 to a conductor 287 which has leads 288 connected to each of the terminals 253.

The brushes 215 are connected by conductors 290a to the terminals 260. The brushes 216 are connected by conductors 290b to the switch arms 251. In the cable 220 (Fig. 1) conductors 290a and 290b are merged into a single conductor 290 which becomes two separate conductors 290a and 290b outside of the cable 220. Brushes 216 are connected by conductor 291a to the switch arms 250. Brushes 216 are connected by conductors 291b to the switch arms 259. Similarly, conductors 291a and 291b in the cable 220 are merged into a single conductor 291.

When a gauge 225 is down, that is to say be-

fore it enters the cylinder bore, switch arms 250 and 251 are closed. This condition is shown for the first three units reading from left to right in Figure 11. Under such conditions, the positive power line 280 being connected to the terminal 252 by the line 281, is connected by the switch arm 250 to the line 291a to the brush 216 which is, therefore, positive. The brush 215 at such times is connected by the line 280b to the switch arm 251 which is in closed position and, therefore, contacts the terminal 253. This terminal 253 is connected by the line 288 to the line 287 to the line 286 to solenoid 140 and thence by way of line 285, rheostat 284 and line 283, to main conductor 275. The brush 215 is, therefore, negative. When the brush 216 is positive and the brush 215 is negative, current flows through the motor in the honing tool in such direction as to revolve the screw shaft 184 to raise the cones 183, thereby expanding the honing sticks 181. It will be noted that under such conditions, the conductor 290a leads to an open circuit and the conductor 291b leads to an open circuit.

When a gauge plug 225 enters its cylinder bore, as indicated in the right-hand unit in Figure 11, switch arms 250 and 251 are opened and switch arms 258 and 259 are closed. Under such conditions positive power line 280 is connected by conductor 281 to switch arm 258, thence by conductor 290a to the brush 215 and the brush 215 is, therefore, positive. Under such conditions the brush 216 is connected by line 291b, switch arm 259, conductor 282, to the power line 275 and the brush 216 is, therefore, negative. This runs the motor in the reverse direction to revolve the screw shaft 184 to lower the cones 183 and the garter springs 185 contract the honing sticks 181. At such times the lines 290b and 291a from the brushes 215 and 216 lead to open circuits.

When the current is directed to the motors to expand the hones or any of them, the current has to go through the solenoid 140. So long as even one gauge plug 225 is down, at least one motor is in what I may call the winding up or expanding condition and current is passing through the solenoid 140 because all of the lines 288 lead to the conductor 286 to the solenoid 140. The electric power factor of the solenoid and the spring 146 are so arranged that with current flowing through even one motor to the solenoid 140, the solenoid overbalances the spring 146. When all of the gauge plugs 225 have advanced into the work piece, current is definitely cut off from the solenoid 140 and then the spring 146 acts to turn the shaft 110 and thereby to turn the dog 114 out of line with the lug 109. Under such conditions the upward stroke of the head 63 is continued to carry the several honing tools out of the bores of the work piece, the head being stopped by the automatic mechanism already described which shifts the stop valve 122.

In the operation of the machine, after a particular gauge has entered a cylinder bore, the motor in the hone is actuated to retract the sticks 181. However, until all of the gauges 225 have entered, the head 63 continues to reciprocate in the lower position. At each downward stroke, the bunters 243 push the gauges 225 out of the cylinder bores and this momentarily opens the switches 258 and 259 and closes the switches 250 and 251. Thereby in the case of such hones as have completed the abrading operation, the motors are energized momentarily to expand the hones. However, the time interval is too short for any substantial amount of expansion and dur-

ing the major part of the working stroke, the motor is energized to contract the hones. The rheostat 284 is provided so that the expansion will be at a slightly lower rate than the contraction, thereby insuring that the hones are always sufficiently collapsed after they have completed the abrading operation.

It will be noted that the motors operate the hones through a screw and through wedge means. This gives the motors a great mechanical advantage. The motors turn very slowly after contact has been made between the sticks 181 and the cylinder wall and, in fact, may be said to exert pressure. The power and windings are such that no winding will burn out even though the armature does not revolve.

In the operation of the machine, the operator first loads a cylinder block in position on the table 4 and this forces down all the gauge plugs 225. He then pushes rearwardly on the knob 157, drawing the pin 154 behind the cam surface 160. A slight amount of lost motion between the hub 151 and the sleeve 125 will permit the pin 154 to be locked in retracted position behind the bracket 118 but at all events the operator may coincidentally operate the knob 157 and the hand lever 133 to close the by-pass valve 122 which causes the fluid to flow first to send the head 63 upwardly for a fraction of an inch, completing the reversal of the valve 88 which reverses the reversing valve 86, sending the head 63 downwardly. The hones will already have been collapsed by the automatic actuation prior to starting up the machine and when they enter the cylinder bores, the operator closes the switch 272 to start the expansion of the hones. The operator opens the switch 272 at the time he changes work pieces and this action insures that the solenoid 140 is deenergized even after the gauges 225 are depressed; thus the spring 146 holds the dog 114 out of the path of the lug 109 to permit the downward movement of the head 63 at the start of the honing operation. The honing operation then proceeds automatically, individual hones collapsing when the bores are ground. When all of the bores are ground, on the next up stroke of the head 63 all the switch arms 250 and 251 are raised and this cuts off current from the solenoid 140 and the spring 146 acts to by-pass the dog 114 so that the head rises where it is ultimately brought to a stop by the cam surface 160 engaging the pin 154, thus throwing the arm 150 to turn the sleeve 125, thereby opening the by-pass valve 122 and coincidentally (if desired) turning the shaft 126 to open the clutch 41 and apply the brake 42, thereby to stop rotation of the hones.

It has been customary to take so much stock out of the cylinder walls of automotive cylinder blocks as the operator in his judgment estimated to be desirable, each honing tool being individually adjusted for a new honing operation. The operators usually have watched the bores and tightened the hones by a number of notches indicated by the previous operation. Cylinder bores have varied in diameter by a matter of a thousandth of an inch or more from the largest to the smallest and have been graded and in the automotive production line different sized pistons have been provided and fitted to the different sized bores. The machine of the present invention is not only automatic but also it is designed to keep on honing until all the bores are honed to a given diameter. Of course, the boring operations will be arranged so that the

largest diameter bore is still slightly undersized to leave some material to be honed. Such a honing operation as herein provided may require the removal of more stock but the operation is entirely automatic after the machine has once been started and the elimination of different sized cylinder bores with as many as five different sizes of pistons being provided to fit them respectively, simplifies later assembly operations and permits the manufacturer to provide one size of pistons instead of five or even more sizes thereof. Pistons can be ground to very close limits with present machines.

Another feature of the present invention is that it may readily be applied to existing machines since the existing controls are utilized, more controls however being added without necessitating rebuilding of the machine. The expansion and contraction device is contained within the honing tool itself which is always a removable part and the gauge units may be incorporated in a special table substituted for the work tables now in use. The control is electric but if the current fails from any cause, the spring 146 acts to stop the machine.

It should be noted that the particular coupling 173 which is described in the Johnson patent is designed to maintain the axis of each honing tool parallel to the others and to a given plane while permitting orbital movement of such axis in counterdistinction to a pair of universal joints which do not hold the driven member in a fixed axial position nor hold the axis of the driven member parallel to a fixed line. It should be noted further that once my honing tool starts to collapse, it collapses completely, subject to slight momentary periods of expansion which are promptly eliminated by further collapsing. Thus it is possible, with the present apparatus, to eliminate the possibility of contact between any of the honing sticks 181 and the bore of a particular cylinder after the same has been honed to the required size.

Referring now to Figure 12, there is therein shown a modification of the structure disclosed in Figure 6 which in some respects represents a preferred embodiment of the invention. At all events, the modification of Figure 12 illustrates the use of a pair of motor armatures to give double the power of the embodiment of Figure 6 and it will be observed that there is plenty of room for downward adjustment of the table 4, as shown in Figure 1, and, therefore, a longer honing tool can readily be used with the machine of this invention. The modification of Figure 12 further provides gearing between the electric motors and the screw shaft 184a. In this embodiment of Figure 12, the gearing involves the use of a pair of large gears, one having one more tooth than the other one so that the increase in torque will be equal to the number of teeth in one of the large gears. In this manner a torque possibly as much as fifty times greater than the torque produced in the apparatus of Figure 6 can be achieved.

Referring specifically to Figure 12, I provide a hub 192a supporting a set of armature arms 193a and 193b forming a pair of armatures each in the form of a cross integrally united to the hub 192a. Surrounding the armatures 193a and 193b are the field magnets 205a which in construction may be the same as the field magnets 205, only thicker in an axial direction. These fit in an outer casing 200a made of brass which is likewise the same as the casing 200, merely longer. In

both embodiments of the invention, the casing 200 or 205a is made of brass so that no short circuit for the magnetic lines of force will be provided.

A central screw shaft 191a provides a mounting for the armatures and is an integral part of a plate 300 which fits in a bearing 301 in a casing 200a. Screw shaft 191a is likewise journaled in a bearing portion 302 which is simply a bore in the spindle 172a. Mounted on the screw shaft 191a is the commutator block 185 with which are associated the other parts already described which need not be further dealt with at this point since the electrical arrangement of the modification of Figure 12 is or may be the same as that of Figure 6.

Fastened to the plate 300 is a stud 305. Mounted on the stud 305 are a pair of gears 306 and 307 formed as an integral piece. A supporting bracket 308 is fastened to the plate 300 and has a journal portion fitting between the gears 306 and 307 to support more rigidly the stud 305 and also the gears. By reason of the construction so far described, the stud 305 is substantially a crank which revolves in a planetary path around the axis of the shaft 191a.

The gear 306 meshes with an internal gear 309 fastened to the casing 200a by means of screws 310. This forms in effect a track for the gear 306 to rotate the same diurnally. The gear 307 meshes with an internal gear 311 formed in a cup member 312 which is an integral part of the shaft 184a. If the number of teeth in the gears 306 and 307 be the same and if the number of teeth in the gears 309 and 311 be the same, gear 311 will not be driven at all since the unit consisting of gears 306 and 307 will simply roll around in the casing. But by making a difference of one tooth in the big gears, with or without a difference of one tooth in the small gears, a differential is achieved. I may select either the gear 308 or the gear 311 to have the greater number of teeth, this matter being substantially immaterial. A very slow rotation of the shaft 184a is the result and the torque on the shaft 184a is equal to the number of teeth in one of the large gears 309 or 311 divided by the difference in teeth (which may be considered to be one) times the torque of the motor less any friction in the parts.

The use of this mechanism achieves improved results because in the operation of my machine there is plenty of time for the motor to act and what is desired is a considerable amount of pressure which can be achieved using two motors or two armatures, the reduction gearing described and a slight angle to the surfaces which fit the cones 183. At the same time using the embodiment of Figure 12, I am enabled to get enough total motion out of the apparatus to use up practically all of the abrasive sticks 181.

It will thus be seen that there has been provided by this invention apparatus in which the various objects hereinabove set forth together with many thoroughly practical advantages are successfully achieved. As many possible embodiments may be made of the above invention and as many changes might be made in the embodiments above set forth, it is to be understood that all matter hereinbefore set forth or shown in the accompanying drawings is to be interpreted as illustrative and not in a limiting sense.

I claim:

1. In a machine tool hone, the combination with a head, a plurality of spindles carried by said head, honing tools on the outer ends of said

spindles, means rectilinearly to move said head including a driving device and controlling devices arranged to reciprocate the head through a limited range to hone a work piece and also to move said head beyond said range to a withdrawn position, and a transmission train to rotate said spindles, of individual gauging devices for gauging the several bores of a work piece being honed by said hones, individual means to collapse said honing tools responsive to indication of completion of the honing operation by said individual gauges, and a control to initiate movement of said head to carry the honing tools away from said limited range, said control being responsive to the gauging devices and operating only when each of the total number of gauging devices have successively gauged and found the work piece bores to have come to desired sizes.

2. In a honing machine, a honing head, a plurality of spindle sockets arranged in parallel relation in said head, means to rotate said spindle sockets in unison, reciprocating mechanism rectilinearly to move said head, controlling mechanism for the reciprocating mechanism to start, reverse and stop the rectilinear movement, individual independent size determining devices the same in number as the number of spindle sockets to measure, apart from counting the reciprocations, the sizes of the bores in a work piece being operated upon, and means controlling the said controlling mechanism for the reciprocating mechanism, and itself under the control of all the size determining devices, arranged and adapted to cause the head to move to and remain in an extreme position only upon the coming to size of the last bore to come to size of a work piece being operated upon by said honing machine.

3. In a honing machine, a honing head, a plurality of spindle sockets in said head, means to rotate the spindle sockets, means rectilinearly to move said head, controlling means for the rectilinear moving means to reciprocate the head in a working position and to cause the withdrawal of the head to a stop position, honing tools carried by said sockets in parallel relation, individual means to expand and contract each honing tool, work piece sizing apparatus, controls to cause the contraction of each honing tool when the work piece bore on which it is working comes to a given size, and means to cause the head to withdraw the honing tools only when all of the work piece bores have reached the given size.

4. In a honing tool, a supporting structure, a plurality of carriers in parallel and radial arrangement and mounted to expand and contract radially, honing sticks carried on said carriers, means to expand and contract said carriers, and an electric motor in the honing tool to actuate said last named means including a permanent field magnet and a commutator whereby reversal in direction of the current procures a reversal of the motor.

5. In a machine of the class described, a plurality of honing tools mounted in parallel relation, means individual to each tool to expand and contract the same, means individually controlled for each tool to cause the same to expand until it reaches a given expansion and then to contract, and means responsive to contraction of all of the honing tools for withdrawing all of them in unison.

6. In a honing tool, a plurality of hone carriers, wedge means to expand the carriers, screw means to operate the wedge means, an electric motor contained in the tool and revolvable as a whole

with it to revolve the screw means, and reduction gearing interposed between the motor and the screw means to give added power.

7. In a honing tool, a plurality of abrasive carriers, means mounting said carriers for radial expansion and contraction, means including a screw shaft to move said carriers, reduction gearing connected to the screw shaft, and an electric motor contained in the tool and revolvable as a whole with it driving the screw shaft.

8. In a honing machine, a work piece support, a support for a plurality of spindles, mechanism to rotate said spindles, a plurality of honing tools one carried by each spindle, a slideway for one of said supports, means to move the last-mentioned support on its slideway to procure a relative reciprocation between said supports for the honing operation and including a device to cause the movable support to travel beyond the range of reciprocation to an inactive position, a plurality of gauging devices one for each honing tool to gauge a plurality of work piece bores independently, a plurality of mechanisms each one controlled by a gauge and each one operative to contract a honing tool independently of the other honing tools, and a mechanism to cause the actuation of the device to cause the movable support to travel beyond the range of reciprocation when all of the plurality of mechanisms have been actuated by the several gauges.

9. In a grinding device for cylinder bores, a plurality of abrading tools, means for driving said tools simultaneously in rotation and reciprocation, a plurality of expandable and retractable

- abrading stones in each tool, means in each tool for expanding said stones within said bore, means in each tool for retracting said stones, and means for actuating said contracting means after a predetermined expansion of said stones, means for moving said tools from the bores, and means actuated after the stones of all of said tools have been retracted for rendering said moving means effective.
10. In a machine tool hone, the combination with a head, a plurality of spindles carried by said head, honing tools on the outer ends of said spindles, means rectilinearly to move said head including a driving device and controlling devices arranged to reciprocate the head through a limited range to hone a work piece and also to move said head beyond said range to a withdrawn position, and a transmission train to rotate said spindles, of a plurality of means each independent of the others in its mechanism and actuation for slowly expanding the several hones, a plurality of controlling devices each independent of the others in its mechanism and actuation for reversing the action to cause contraction of said hones individually, and a coordinated controlling apparatus connected to said controlling device for reversing the action and operating upon the controlling devices to move said head beyond said range and operating to initiate said movement of said head to beyond said range after and only after each of said plurality of controlling devices for reversing the action has operated.

GEORGE CROMPTON, JR.
